(57) **CLAIM**

The ornamental design for an inflatable neck pillow, as shown and described.

DESCRIPTION

FIG. 1.1 is a top view of the inflatable neck pillow;
FIG. 1.2 is a perspective bottom view on an open position of the inflatable neck pillow;

FIG. 1.3 is a perspective top view on an open position of the inflatable neck pillow;

FIG. 1.4 is a perspective top view on an open position of the inflatable neck pillow in a deflated state;

FIG. 1.5 is a back view on an open position of the inflatable neck pillow;

FIG. 1.6 is a front view on an open position of the inflatable neck pillow;

FIG. 1.7 is a right side view on an open position of the inflatable neck pillow;

FIG. 1.8 is a left side view on an open position of the inflatable neck pillow;

FIG. 1.9 is a perspective bottom view on an open position of the inflatable neck pillow in a deflated state; and

FIG. 1.10 is a bottom view of the inflatable neck pillow.

FIG. 2.1 is a perspective bottom view on an open position of the inflatable neck pillow;

FIG. 2.2 is a top view of the inflatable neck pillow;

FIG. 2.3 is a perspective top view on an open position of the inflatable neck pillow;

FIG. 2.4 is a perspective top view on an open position of the inflatable neck pillow in a deflated Fig. state;

FIG. 2.5 is a back view on an open position of the inflatable neck pillow;

FIG. 2.6 is a front view on an open position of the inflatable neck pillow;

FIG. 2.7 is a right side view on an open position of the inflatable neck pillow;

FIG. 2.8 is a left side view on an open position of the inflatable neck pillow;

FIG. 2.9 is a perspective bottom view on an open position of the inflatable neck pillow in a deflated state; and

FIG. 2.10 is a bottom view of the inflatable neck pillow.

FIG. 3.1 is a perspective bottom view on an open position of the inflatable neck pillow;

FIG. 3.2 is a top view of the inflatable neck pillow;

FIG. 3.3 is a perspective top view on an open position of the inflatable neck pillow;

FIG. 3.4 is a perspective top view on an open position of the inflatable neck pillow in a deflated state;

FIG. 3.5 is a back view on an open position of the inflatable neck pillow;

FIG. 3.6 is a front view on an open position of the inflatable neck pillow;

(Continued)

FIG. 3.7 is a right side view on an open position of the inflatable neck pillow;
 FIG. 3.8 is a left side view on an open position of the inflatable neck pillow;
 FIG. 3.9 is a perspective bottom view on an open position of the inflatable neck pillow in a deflated state; and
 FIG. 3.10 is a bottom view of the inflatable neck pillow. Inflatable neck pillows which are shapeable even in inflated state between an extended straight position and at least one bent position.
